Primary Examiner — Richard Kearney*Assistant Examiner* — Landon Thomas Cassell(74) *Attorney, Agent, or Firm* — Chun-Ming Shih; hdls ipr services(57) **CLAIM**

The ornamental design for a vibration device as shown and described.

DESCRIPTION

FIG. 1 is a first perspective view of a vibration device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a second perspective view thereof; and,

FIG. 9 is another perspective view thereof. The additional broken lines show an acupuncture suction cup that form no part of the claimed design.

The evenly spaced broken lines shown in the figures depict portions of the vibration device that form no part of the claimed design. The dot-dot-dash broken lines shown in FIG. 9 depict environment and form no part of the claimed design.

1 Claim, 9 Drawing Sheets(56)
